CARRIER DISPATCH SYSTEM

Frank W. MacMartin, Syracuse, N. Y., assignor
to The Lamson Company, Syracuse, N. Y., a
corporation of Massachusetts

Application January 21, 1930, Serial No. 422,313

23 Claims. (Cl. 243—1)

This invention pertains to carrier dispatch systems such as are employed in banks, large business offices, industrial establishments, and the like, for transmitting documents, publications, messages, small articles of merchandise, etc., from one department, officer, or operator to another, and finds its greatest utility in systems of highly complex character involving a great number of stations such, for instance, as are found in the home offices of the large insurance companies, such systems being characterized by the capability of transmitting carriers from any one of a large number of stations to any other station.

In accordance with the present invention and in order to avoid undue complexity of mechanical parts, I provide a transfer or relay station as an essential part of the system, such station being so connected to each of the sending stations that all carriers pass through it on their way from one station to another, and being so designed as to permit the number of operators at such relay or transfer station to be varied in accordance with changes in the volume of business without substantial sacrifice in efficiency. In such a system as above described, as distinguished from the ordinary store service system, carriers do not necessarily return to the station from which they are first sent, and in accordance with the present invention provision is made for replenishing the supply at any given station when such supply has been reduced or exhausted.

While I have herein chosen to illustrate the invention as embodied in a pneumatic tube dispatch system, I wish it to be understood that the broader features of the invention may likewise be embodied in dispatch systems of other types, and further, while I have herein illustrated one specific arrangement of transfer or relay station which has been found convenient, efficient and saving of space, I wish it to be understood that the invention may embody other forms of transfer station and other specific arrangements of parts and means for moving carriers than those herein shown and described.

In the accompanying drawings, wherein I have illustrated a preferred embodiment of the invention:

Fig. 1 is a diagrammatic plan view illustrating the general arrangement of the transfer or relay

station and its relation to the sending stations;

Fig. 2 is a diagrammatic elevation illustrating parts of the system shown in Fig. 1;

Fig. 3 is a plan view showing one desirable arrangement of conveyor belts, driving motors, and chutes at the transfer station;

Fig. 4 is a diagrammatic vertical section on the line 4—4 of Fig. 3;

Fig. 5 is a diagrammatic side elevation substantially in the plane of line 5—5 of Fig. 3; 10

Fig. 6 is a diagrammatic front elevation of the station of Fig. 1;

Fig. 7 is a vertical section illustrating a set of distributing chutes;

Fig. 8 is a side elevation of one desirable form 15 of requisition carrier; and

Fig. 9 is a section on the line 9—9 of Fig. 7.

Referring to the drawings, and particularly to Fig. 2, A represents a building devoted in whole or in part to the business served by the apparatus 20 of the present invention, such building being of any desired height and having floors a and usual partitions dividing the enclosed space into office or other rooms which may be grouped in any way to house distinct departmental activities of 25 the business, and in any of which offices or rooms may be located sending stations S of the carrier dispatch system. The several stations communicate by means of suitable conveyors, for example pneumatic tubes, with a transfer station T, conveniently located in the basement of the building. 30

The transfer station selected for illustration, as shown diagrammatically in Fig. 1 and in plan in Fig. 3, comprises endless conveyor belts 11, 12, 13, 14, 15, 16, 17 and 18, the various conveyors preferably being arranged for transporting carriers through a path which follows a course similar to the letter U. Substantially vertical guides or side boards 20 are disposed along the outer marginal edges of the various conveyors. At the 40 base of the U are assorting stations 21, 22, 23, 24, 25 and 26 and along the inner sides of the U adjacent the conveyors 16 and 18 are dispatching stations 27, 28, 29, 31, 32, and 33, while delivery terminals 34, 35, 36 and 37 are disposed along conveyors 11 and 13 respectively at the outer sides of the U. The arrangement of the conveyors in a U-shaped system is economical of space, and as the various assorting and dispatching stations are on the inner sides of the U, it is assured that 50

an operator may move readily from one station to another, thus facilitating handling of the work and making it possible for one operator to take care of more than one station should this be desirable.

The various conveyors operate in the direction indicated by the arrows. Conveyors 11 and 13 at the outer sides of the U serve to transport carriers from the receiving stations 34, 35, 36 and 37 to the conveyors 12 and 14, respectively, the latter serving to deliver carriers into an inclined chute 38 which terminates at its lower end between assorting stations 23 and 24. An operator positioned at one or both of these stations may pick up carriers as they are delivered by the chute 38 and sort them for their destination. At busy times, however, operators at these stations might be unable to handle this work, and for expediting the work during periods of intensive service the auxiliary chutes 39 and 41, similar to chute 38, are arranged to deliver some of the carriers from conveyors 12 and 14 respectively to operators positioned at stations 21, 22 and 25 and 26, respectively.

In order that the incoming carriers may be distributed approximately equally between the various assorting stations 21 to 26, the traveling surface of each of the conveyors 11, 12, 13 and 14 is divided longitudinally by centrally disposed vertical partitions 42, 43, 44 and 46 respectively. It will thus be seen that the partition 42 divides the conveyor 11 into lanes 11^a and 11^b which communicate with lanes 12^a and 12^b formed by the partition 43. These lanes all lead directly to the centrally disposed chute 38. At the mouth or receiving end of chute 41 a deflector, such as the vane 47, is mounted to pivot so that it may be swung diagonally across lane 12^b to direct incoming carriers into the chute 41. This deflector may also be swung to position parallel to the conveyor and at the side thereof to allow all carriers to be delivered directly into the middle chute 38 should this be desired. Similarly a vane 48 is mounted at the receiving end of chute 39 so as to serve as a deflector when positioned transversely of the lane 14^b, and obviously when the vane 48 is swung to a position at one side of the conveyor, carriers will pass through the lane 14^b directly to the central chute 38. The vanes 47 and 48 may be provided with operating arms 49 and 51 respectively. It will be seen, therefore, that carriers issuing from delivery terminals 34 will pass through lanes 11^a and 12^a to the middle chute and likewise carriers from delivery terminals 36 will pass through lanes 13^a and 14^a to the same chute. On the other hand, carriers issuing from delivery terminals 35 and 37 will be conducted through lanes 11^b, 12^b and 13^b, 14^b, respectively, and these carriers may be allowed to pass directly to the chute 38 or may be diverted through the auxiliary chutes should this be desirable. In this way a very flexible arrangement is provided for taking care of incoming carriers. Normally, only one operator need be stationed at each of the assorting stations 21 to 26 and under some conditions, as when business is light, one operator may tend to more than one station, or some of the stations may be closed. However, it will be understood that the number of operators at any or all of the stations may be increased whenever this is considered advisable.

In front of each operator's position at assorting stations 21 to 26 a number of openings are formed in the table top and these openings are

connected by means of slides or chutes with a corresponding number of lanes on the conveyors 15, 16, 17 and 18. For the purposes of illustration, each of these conveyors has been divided into three lanes, although it will be understood that the number of lanes may be varied to suit conditions. Longitudinally extending vertical partitions 52, 53, 54, 55 divide conveyors 15 and 16 respectively into lanes 15^a, 15^b, 15^c and 16^a, 16^b and 16^c. Similarly partitions 56, 57, 58 and 59 divide conveyors 17 and 18 respectively into communicating lanes 17^a, 17^b, 17^c and 18^a, 18^b, 18^c. Adjacent to the dispatch stations 21, 28, 29 and 31, 32, 33 deflectors 61, 62 and 63 cooperate with the partitions 54, 55, 58, 59 and with 15 the guide boards 20 to assist in directing carriers from the various lanes to the proper group of dispatch stations.

At the assorting stations 21 to 26 (Fig. 3), openings 50^a, 50^b and 50^c communicate respectively with lanes 15^a, 15^b and 15^c, while openings 60^a, 60^b and 60^c communicate respectively with lanes 17^a, 17^b and 17^c. An operator at any one of the stations 21 to 26 may send a carrier to any dispatch station in the groups 27 to 29 25 and 31 to 33 by depositing the carrier in the opening communicating with the lane which leads to the group in which the desired station is included. Pneumatic tubes 64 lead from these dispatch stations to the stations S 30 (Fig. 1) located in the various offices or at other desired points, and return tubes lead from the stations S to the delivery terminals 34, 35, 36, 37, etc. at the transfer station.

To further expedite the service, certain busy 35 lines, such for example as those leading to the mailing and filing departments, may terminate directly at the sorters' section in front of assorting stations 21 to 26. These lines are indicated generally at 68 in Fig. 2 and are provided with 40 suitable receiving and dispatch terminals. These lines are preferably arranged in groups comprising receiving and sending units 69 and 71 respectively which terminate at the sides of the chutes 38, 39 and 41, as indicated in Figs. 1, 4, 5 and 6. 45 Furthermore, certain lines may lead directly from one department to another, as indicated by the lines 72, 73 (Fig. 2) which lead directly from stations 74, 75 to stations 77 and 78.

It will be seen from Fig. 6 that the conveyors 50 12 and 14 which lead directly to the chutes 38, 39 and 41 are disposed above conveyors 15 and 17 which conduct carriers away from the assorting stations 21 to 26. This is a compact, efficient arrangement which is economical of space and 55 makes it possible to discharge carriers from conveyors 12 and 14 to the assorting table and thence to conveyors 15 and 17 by gravity. Conveyors 11 and 13 (Figs. 4 and 5) disposed along the outer sides of the U, follow substantially horizontal paths from end rollers 91 (Figs. 3 and 4) to intermediate rollers 92 about which the upper course of the belt turns backwardly and around idler rollers 93 and then forwardly in an upwardly 60 inclined direction to end rollers 94 disposed at 65 the mouths or receiving ends of chutes 96. These chutes have partitions 42', 44' (Fig. 6) corresponding to partitions 42, 44, and are arranged to discharge carriers in the proper lanes on conveyors 12 and 14. From the end rollers 94 the belts of conveyors 11 and 13 pass downwardly and backwardly around suitable idler rollers 97, 98 to the end rollers 91.

Conveyors 12 and 14 operate over end rollers 75

101, 102, (Fig. 6) and conduct carriers received from chutes 96 up an inclined path to a substantially horizontal course which leads past the auxiliary chute 39 (or 41) to the central chute 38. 5 Conveyors 15 and 17 operate respectively over end rollers 103, 104 and 106, 107 and serve to discharge carriers through chutes 108^a, 108^b, 108^c, and 109^a, 109^b, 109^c (Figs. 4 and 5) respectively onto the proper lanes of conveyors 16 and 18. Directly beneath these chutes the conveyors 16, 18 10 operate in upwardly inclined paths to transport carriers deposited thereon upwardly and then in a substantially horizontal direction to the groups of dispatching stations 27 to 29, 31 to 33. The end 15 rollers for conveyors 16, 18 are indicated at 111, 112 and suitable intermediate and idler rollers at 113, 114. The various conveyors 11, 18 may be operated by individual motors 140 or in any other approved manner. A group of slides through 20 which carriers pass from openings 50^a, 50^b, 50^c, 60^a, 60^b, 60^c, (Fig. 3) at the assorting stations to the conveyors 15 and 17 are shown in Figs. 4, 7 and 9. From these views it will be seen that the slide 116 (Fig. 7) which serves an opening 50^a is substantially vertical, while the remaining slides 117 25 to 121 are inclined at the proper angles to conduct carriers from the remaining openings to the proper lane. Thus slide 117 is adapted to conduct carriers from an opening 50^b to the lane 15^b, slide 30 118 connects an opening 50^c with the line 15^c, while slides 119, 120 and 121 afford communication respectively between openings 60^a, 60^b, 60^c and the lanes 17^a, 17^b, and 17^c. These slides are preferably in the form of chutes having a rectangular cross section with outwardly directed top flanges *f* as shown in Fig. 9 and these chutes terminate directly at the partitions which divide the conveying surface into the various lanes. As shown particularly in Fig. 7, the partitions are 35 preferably in the form of spaced plates 122, 123 having overlapping flanges at the bottom and connected at the top to the depending flanges of angles 124 spaced back-to-back and separated by the spacing strip 126, the angles 124 being supported from an upper transverse support such as the angle 127 which in turn is supported from the side boards or guides. As shown in Fig. 7 these side boards may be formed of plates 128 having stiffening angles 129 attached along their upper 40 and lower edges and, of course, it will be understood that suitable framework is provided, as indicated generally at 130 in Figs. 4, 5 and 6, for supporting the guideboards and partitions. It will also be understood that the arrangement of partitions and the guide boards, as shown in Fig. 7 for the conveyors 15 and 17, may be substantially the same as that used on other conveyors and for this reason further illustration of this feature is deemed unnecessary. 45

50 As previously pointed out this system of carrier distribution is particularly useful in handling carriers which are not opened previous to reaching their destination. The carriers may be marked with a color scheme to indicate the group of stations 27-29 or 31-33 to which they are to be sent. The carriers may also carry numbers or other indicia to designate the particular tube at these stations through which they are to be dispatched. 55

The carriers are first delivered to the primary sorter's table 131 (Fig. 1) where they are sorted by operators according to their color scheme and dispatched into the proper lanes which may also be indicated with corresponding colors. On reaching a secondary sorter's table 132 or 133 the carriers are then redispatched by number through 60

the proper tube. If color group designation is not employed, the dispatch tubes may be grouped by numbers and carriers having numbers within any such group will be delivered to the proper dispatch operator through the appropriate lane by the operator at the sorter's table 131. Obviously, any other suitable system of designation may be used. This arrangement leaves the sorting to be done by one or two operators at the chute 38 alone, or when business warrants with additional operators located at chutes 39 and 41 thereby providing great flexibility in the number of operators according to the volume of the business to be handled. 10

As this system provides service to such a large 15 number of stations, a rover system of carrier distribution has been devised whereby a certain number of carriers are assigned proportionately to each sub-station. A stock of additional carriers is kept at the main transfer station. Carriers arriving at each sub-station are retained there after their contents are removed until the supply becomes excessive, and then these empty carriers are sent back to the transfer station to be put into the reservoir supply. If the supply at the 20 sub-station becomes depleted it is necessary to requisition additional carriers from the main supply. For this purpose a single carrier 135 (Fig. 8) is provided to serve as a requisition for additional carriers. The carrier 135 follows a standard carrier in form and size and differs only in that the open end is closed with a suitable plug 136 to prevent its use for dispatching papers, and a distinctive color band 137 is painted around the shell on which is marked the sub-station number (*x*) to 25 which this carrier belongs. When one of these carriers is received at a transfer station it is passed along to the operator in charge of carrier supply and a suitable number of empty carriers are then sent to the station indicated on the requisition carrier with the signal carrier following the requisitioned carriers. 30

While apparatus of preferred form has here been shown as illustrative of the invention, it is to be understood that the invention is not necessarily 45 limited to this particular embodiment but that changes in shape, size, number, and relative arrangement of parts as well as the substitution of equivalents fall within the scope of the invention.

I claim:

1. A carrier dispatch system of the kind having a plurality of sending stations and carriers which travel unopened from one such station to another, and a relay station interposed in the path of carriers moving from one sending station to another, said relay station comprising means adapted to receive carriers from any of said sending stations, an assorting station, a plurality of redispach stations each having dispatch terminals, each said terminal communicating with one of the sending stations, and means for causing carriers to move from the assorting station to any selected dispatch station. 55

2. A carrier dispatch system of the kind having a plurality of sending stations and carriers which travel unopened from one such station to another, and a relay station comprising means adapted to receive carriers from any of said sending stations and to deliver a part of said 70 carriers to one assorting station and a part of said carriers to another assorting station, a plurality of redispach stations each having dispatch terminals, each such terminal communicating with a sending station, and means for moving car- 75

- riers from any one of the assorting stations to any selected redispach station.
3. A carrier dispatch system of the kind having a plurality of sending stations and carriers which travel unopened from one such station to another, and a relay station comprising means adapted to receive carriers from any of said sending stations and to deliver all of said carriers to a single assorting station or alternatively to deliver a part of said carriers to one assorting station and a part to another assorting station, a plurality of redispach stations, and means common to the several assorting stations for conveying carriers from the latter to any selected redispach station.
4. An intercommunicating carrier dispatch system of the kind having a plurality of sending stations and carriers which travel unopened from one of said stations to another, a relay station comprising an assorting station at which the carriers are manually sorted and a plurality of redispach stations, means for delivering all carriers arriving at the relay station from the several sending stations to the assorting station, and independent conveyors leading from the assorting station to the several redispach stations.
5. An intercommunicating carrier dispatch system of the kind having a plurality of sending stations and carriers which travel unopened from one of such stations to another, a relay station comprising an assorting station and a plurality of redispach stations, means for delivering all carriers arriving at the relay station from the several sending stations to the assorting station, conveyor means for transferring carriers from the vicinity of the assorting station to the several dispatch stations, and means for delivering carriers from the assorting station to any selected conveyor means.
6. An intercommunicating carrier dispatch system of the kind having a plurality of sending stations and carriers which travel unopened from one of such stations to another, a relay station comprising a plurality of assorting stations, a plurality of redispach stations, means operative to deliver all carriers arriving at the relay station from the several sending stations to one of the assorting stations or alternatively to deliver a part of the arriving carriers to one assorting station and a part to another assorting station, a plurality of independent conveyors leading to the respective redispach stations, and means for delivering carriers from any of the assorting stations to any of said independent conveyors.
7. An intercommunicating carrier dispatch system of the kind having a plurality of sending stations and carriers which travel unopened from one of such stations to another, a relay station comprising a plurality of assorting stations, a plurality of redispach stations, means operative to deliver all carriers arriving at the relay station from the several sending stations to one of the assorting stations or alternatively to deliver a part of the arriving carriers to one assorting station and a part to another assorting station, conveyors for moving carriers from the several assorting stations to each of the redispach stations, and independent chutes leading from each assorting station to each of said conveyors.
8. An intercommunicating carrier dispatch system of the kind having a plurality of sending stations and carriers which travel unopened from one of such stations to another, a relay station comprising an assorting table, a delivery chute leading thereto, a plurality of redispach stations, conveyor means adapted to receive carriers from the several sending stations and to deposit them in the delivery chute, and conveyor means for receiving carriers from the assorting table and transferring them to any selected redispach station.
9. An intercommunicating carrier dispatch system of the kind having a plurality of sending stations and carriers which travel unopened from one of such stations to another, a relay station comprising an assorting table, a delivery chute leading thereto, a plurality of receiving conveyors to which carriers are delivered from certain groups respectively of sending stations, said conveyors being adapted to deliver all such carriers to the assorting table, a plurality of redispach stations having dispatch terminals corresponding respectively to certain groups of sending stations, and means for transferring carriers from the assorting table to any selected redispach station.
10. An intercommunicating carrier dispatch system of the kind having a plurality of sending stations and carriers which travel unopened from one of such stations to another, and a relay station comprising spaced parallel conveyor belts, a plurality of delivery terminals arranged to deliver carriers from certain of said sending stations to each of said belts, an assorting station, a chute at said station arranged to permit an operator to work at either side thereof, means for transferring carriers from each of said conveyor belts to said assorting station, redispach terminals arranged in a plurality of separate banks, and means within convenient reach of each operator at the assorting table for receiving carriers for delivery to any of said banks of redispach terminals.
11. An intercommunicating carrier dispatch system of the kind having a plurality of sending stations and carriers which are dispatched from one of said stations to another, and a relay station comprising spaced parallel conveyor belts, a plurality of delivery terminals arranged to deliver carriers from certain of said sending stations to each of said belts, transfer belts transverse to said conveyor belts adapted to receive carriers from the latter, and a plurality of assorting chutes, said transfer belts being adapted to deliver all carriers to one of said chutes, and adjustable means associated with said transfer belts for optionally diverting carriers carried by each transfer belt to another chute.
12. An intercommunicating carrier dispatch system of the kind having a plurality of sending stations and carriers which are dispatched from one of said stations to another, and a relay station comprising spaced parallel conveyor belts, a plurality of delivery terminals arranged to deliver carriers from certain of said sending stations to each of said belts, a plurality of banks of redispach terminals arranged substantially parallel to each conveyor belt, a row of assorting stations interposed between said belts, chutes substantially parallel to the belts for delivering carriers to the respective assorting stations, transfer means for delivering carriers from the belts to the chutes, a plurality of parallel conveyors comprising portions extending along the row of assorting stations, said conveyors corresponding to the several banks of redispach terminals, and chutes at each assorting station for delivering carriers.

carriers to any selected one of the parallel conveyors.

13. An intercommunicating dispatch system of the kind having a plurality of sending stations and carriers which travel unopened from one of such stations to another, a relay station interposed between a pair of such sending stations, said relay station comprising a plurality of chutes each arranged to permit an assorting operator to be stationed at each side thereof, means for delivering all arriving carriers to one of said chutes or alternatively to deliver a part of said carriers to one chute and a part to another, redispach terminals disposed in banks remote from said chutes, and conveyor means accessible to any assorting operator stationed at any of the respective chutes for transferring carriers to any selected bank of redispach terminals.

14. An intercommunicating carrier dispatch system of the kind having a plurality of sending stations and carriers which travel unopened from one of such stations to another, and a relay station substantially U-shaped in plan interposed between a pair of such sending stations, said station having receiving and dispatch terminals arranged along the parallel legs of the U and an assorting station at the closed end of the U, and means for transferring carriers from the receiving terminals to the assorting station and from the assorting station to the redispach terminals.

15. An intercommunicating carrier dispatch system of the kind having a plurality of sending stations and carriers which are dispatched from one of said stations to another, and a relay station comprising substantially parallel conveyor devices, and delivery terminals associated with each such conveyor device for delivering carriers from sending stations thereto, an assorting station disposed between said conveyor devices, means for transferring carriers from the respective conveyor devices to the assorting station, a plurality of banks of redispach terminals, said banks being disposed substantially parallel to said conveyor device, and means for transferring carriers from the assorting station to the several banks of redispach terminals.

16. An intercommunicating carrier dispatch system of the kind having a plurality of sending stations and carriers which are dispatched from one of said stations to another, and a relay station comprising a plurality of conveyors, two rows of delivery terminals for delivering carriers from sending stations to each conveyor, means providing separate paths for the carriers delivered from the respective rows of terminals as they are moved along by the conveyors, a plurality of assorting chutes, deflector means adjustable to cause all carriers on the conveyors to enter one of said chutes or alternatively to cause carriers moving in one carrier path to enter one chute and carriers in another carrier path to enter another chute, redispach terminals, and means for transferring carriers assorted at said chutes to the redispach terminals.

17. An intercommunicating carrier dispatch system of the kind serving a plurality of distinct departments each including a plurality of sending stations and carriers having primary index characteristics corresponding to departments and secondary index characteristics corresponding to individual sending stations, said carriers being designed for dispatch from any station to any other station of the system, and a relay station through which carriers on their way from

one sending station to another must pass, said relay station comprising a primary assorting station at which carriers are manually assorted in accordance with their primary index characteristics, and a secondary assorting and redispach station, corresponding to each of the several departments, where carriers are assorted in accordance with their secondary characteristics and forwarded to the corresponding sending stations, and independent means for transferring carriers having different primary characteristics from the primary assorting station to the several redispaching stations.

18. An intercommunicating carrier dispatch system of the kind serving a plurality of sending stations and having carriers designed to be sent from any station of the system to any other station, a reserve station through which all carriers pass on their way from one sending station to another, and a requisition carrier for each sending station having characteristics identifying its station, said requisition carrier being so constructed as to preclude its use for general purposes but being adapted for dispatch from its sending station to the reserve station to notify an operator at the latter station whenever the supply of carriers at said sending station requires replenishment.

19. An intercommunicating carrier dispatch system of pneumatic type designed to serve a plurality of sending stations and having carriers adapted to receive material to be sent from any station to any other station of the system, a reserve station through which all carriers pass on their way from one sending station to another, and a requisition carrier for each sending station, said requisition carriers being similar to the other carriers but being permanently closed to prevent their use as regular carriers and having index characteristics identifying their respective sending stations, said requisition carriers, when delivered at the reserve station, giving notice to the operator at such station of the depletion of the supply of usual carriers at the station from which the requisition carrier was sent.

20. A carrier dispatch system of the kind having a plurality of sending stations and carriers which travel unopened from one such station to another, and a relay station interposed in the path of travel of carriers moving from one such station to another, said relay station comprising means for receiving carriers and for redispaching carriers.

21. A carrier dispatch system of the kind having a plurality of sending stations and carriers which travel unopened from one such station to another, and a relay station interposed in the path of travel of carriers moving from one such station to another, said relay station comprising carrier receiving means, an assorting station, and redispach means.

22. A method of dispatching carriers at a central station in a pneumatic carrier system which comprises segregating a plurality of carriers at a distributing point into groups coordinated with their ultimate destinations according to external appearance, transmitting each group of carriers to a separate dispatching station, and inserting the carriers at each station in the appropriate tube corresponding to the ultimate destination.

23. A method of dispatching carriers from one point to any one of a plurality of other points in a pneumatic dispatch system which comprises

numbering the destination points and dividing them into groups, selecting at the sending point a carrier of characteristic appearance corresponding to the groups of the desired destinations, designating on the carriers the particular destinations within the groups, delivering the

carriers to a distributing station for sorting into the groups, transmitting each group to a separate dispatch station, and dispatching the carriers at each such station to the ultimate destinations designated on the carriers.

FRANK W. MACMARTIN.
